METHOD OF EXHAUST

George A. Freeman, East Orange, N. J., assignor
to Westinghouse Electric & Manufacturing
Company, East Pittsburgh, Pa., a corporation
of Pennsylvania

Application October 8, 1940, Serial No. 360,219

5 Claims.

(Cl. 176—2)

The present invention relates to the method of seasoning lamps and particularly to lamps of the high pressure mercury type.

Lamps of this type have heretofore been seasoned during exhaust on an automatic exhaust machine provided with an indexing table. In order to increase production in the interests of economy of manufacture, the various positions of the indexing table to which the lamps are moved are necessarily of short duration. During one of the positions of the indexing machine, the high pressure mercury lamp is connected to an exhaust pump and, while so connected, it is customary to initiate and sustain an arc discharge between the electrodes in order to heat the same to a temperature sufficient to drive off occluded gases, which are thus withdrawn by the vacuum pump.

However, during such automatic exhaust, the arcing of the electrodes is necessarily brief because of rapid indexing of the machine. As a consequence, difficulty in seasoning lamps of the high pressure mercury vapor type has been encountered. Investigation has shown that this difficulty is due to the presence of hydrogen in the electrodes which is not completely driven off during the brief period of arcing on the automatic exhaust machine, and as a result the hydrogen is eventually evolved, which tends to quench an arc once it has been started, and higher open circuit voltage is customarily required to maintain the arc.

It is accordingly an object of the present invention to provide a method of seasoning lamps of the high pressure mercury vapor type wherein the occluded gas is completely removed, which thus renders the open circuit voltage required to be maintained substantially constant.

Another object of the present invention is the method of seasoning lamps of the high pressure mercury vapor type wherein occluded hydrogen is completely removed from the lamp after sealing off by heating the electrodes to a temperature sufficient to drive off the occluded hydrogen, which is diffused through the heated envelope and withdrawn by the vacuum pump.

Still further objects of the present invention will become obvious to those skilled in the art by reference to the accompanying drawing wherein:

Fig. 1 shows a lamp of the high pressure mercury vapor type in the first step of seasoning in accordance with the present invention.

Fig. 2 illustrates the same lamp in the second seasoning step in accordance with the present invention wherein the electrodes are heated by

the initiation and maintenance of an arc discharge between the electrodes.

Fig. 3 shows the lamp of Fig. 1 in the third seasoning step of the present invention wherein the lamp is cooled and exhausted.

Fig. 4 shows the lamp in the fourth step in seasoning of the lamp in accordance with the present invention.

Fig. 5 illustrates the lamp in the fifth step in seasoning of the same in accordance with the present invention.

Fig. 6 illustrates an apparatus for housing the lamps during seasoning in accordance with the present invention.

Referring now to the drawing in detail, the lamp as shown in Fig. 1 is of the type shown and described more in detail in the copending application, Ser. No. 284,576, filed July 15, 1939, of which I am a co-inventor, and which is assigned to the same assignee as the present invention. Since the present invention is not directed to the structure of the lamp per se, it is believed unnecessary that the same be herein described in detail.

It should suffice to say that the lamp comprises an envelope 5 composed of a vitreous material, such as quartz or a material having 80% or more of quartz, which is capable of withstanding the high temperatures during operation of the lamp. The envelope 5 as shown is provided with a pair of electrodes 6 and 7 sealed therein and supported by a pair of bridges 8 and 9 which are suspended between a pair of leading-in and supporting conductors 10 and 12.

These leading-in and supporting conductors are sealed into a press portion 13 forming part of an outer surrounding envelope 14, with the latter being provided with an exhaust stem 15 for exhaust purposes. The electrode 6 as shown is connected to the leading-in conductor 10 by a flexible conductor 16, and the electrode 7 is connected by a similar flexible conductor 17 to the leading-in conductor 12. A starting electrode 18 is connected through an impedance device 19 to the leading-in conductor 10.

Each end of the quartz envelope 5 is provided with a metallic reflecting shield 20 for the purpose of conserving heat. The high pressure mercury vapor lamp 5, as is customary in the art, is first exhausted on an automatic exhaust machine provided with an indexing table, as above noted. In one of the positions of the indexing table and while the quartz envelope 5 is connected to a vacuum pump, a potential is applied to the electrodes to initiate and sustain an arc

discharge, which is of approximately fifteen seconds duration, before the lamp is moved to the next indexing position. Subsequently the lamp is filled with an inert gas and a small quantity of mercury and sealed off at an exhaust tip, such as shown at 22. The electrodes of the lamp 5 are accordingly subjected to seasoning only for a period of approximately fifteen seconds, which is insufficient for the occluded hydrogen to be completely driven from the electrodes.

During the life of the lamp and continued heating of the electrodes by the discharge, the hydrogen is eventually driven off, which tends to quench the arc, thus requiring higher open circuit voltage to maintain the arc. In order to overcome this difficulty, the method of the present invention comprises arcing the lamps during exhaust of the outer surrounding envelope. In carrying out such method, the sealed lamp 5 is accordingly mounted in the outer envelope and the latter connected to a vacuum pump, in the manner shown schematically in Fig. 1. After the outer envelope is subjected to a vacuum pump for a short period of time, a high voltage current is applied to the electrodes 6 and 7 of the lamp 5 from a suitable source of supply, such for example as a high voltage transformer 23, the primary winding 24 of which may be connected to a source of supply of the customary domestic potential of 115 or 230 volts.

The secondary winding 25 which generates approximately 500 volts is connected to the leading-in conductors 10 and 12 and thus to the electrodes 6 and 7 of the lamp 5. An impedance device 26 is provided in series with the lamp 5 and the secondary winding 25 to limit the arcing current and, as shown schematically in the several figures, one or more lamps may be simultaneously seasoned by connecting the lamps in a series circuit.

Upon closure of a suitable switch 27, the high voltage current will accordingly be applied to the electrodes 6 and 7, which initiates a discharge therebetween. This discharge is continued for a period of approximately five minutes, with the result that the electrodes 6 and 7 are heated to a temperature sufficient to drive off occluded gas, and particularly hydrogen.

Since the quartz envelope 5 is also heated by the discharge to a relatively high temperature, the hydrogen diffuses through the heated wall of the quartz envelope into the outer envelope 14 and, since the latter is in direct communication with the vacuum pump during the continuance of the discharge, the gas diffused through the quartz envelope is thus withdrawn from the outer envelope 14.

At the same time, the heat generated by the discharge bakes the outer envelope, thus removing water vapors therefrom and eliminating the former baking step heretofore required prior to sealing off of the outer envelope. Moreover, the hydrogen is forever removed from the lamp instead of being left in the outer envelope where it can again diffuse back into the quartz envelope 5 during normal life of the lamp. After arcing of the lamp during exhaust, as shown in Fig. 2, the arc is extinguished, as shown in Fig. 3, to allow the lamp to cool while evacuation is continued. The outer envelope 14 may then be filled with an inert gas such as nitrogen, if desired, after which the lamp is tipped off, as shown in Fig. 5.

As previously mentioned, two or more lamps may simultaneously be seasoned and in order to conserve heat so that the outer envelope 14 will

be adequately baked by the heat generated by the discharge, the several lamps may be housed within a container 28, such as shown in Fig. 6. It will thus be seen that by employing the method 5 herein described, the high pressure mercury vapor lamp may be partially seasoned on an automatic exhaust machine and completely sealed off, after which it can be completely seasoned during exhaust of the outer envelope, thus removing all of the gas which might otherwise diffuse back into the discharge lamp during life.

It can thus be readily seen that a lamp is produced by the present method wherein the open circuit voltage required to maintain the arc remains substantially constant during the entire 15 life of the lamp. Moreover, arcing of the lamp while on the automatic exhaust machine may be eliminated if desired and seasoning of the electrodes carried out entirely during exhaust of the outer envelope.

In addition, by seasoning the high pressure mercury vapor lamp during exhaust of the outer envelope, the latter is heated to a temperature sufficient to bake the moisture therefrom without the necessity for an oven bake as heretofore required, which thus materially decreases the entire manufacturing cost of seasoning and exhausting.

Although one specific embodiment of the present invention has been shown and described, it is to be understood that still further modifications of the same may be made without departing from the spirit and scope of the appended claims.

I claim:

1. The method of seasoning high pressure mercury vapor lamps which comprises sealing off the quartz envelope containing the electrodes, mounting the sealed envelope in an outer envelope, energizing the lamp to initiate and sustain an arc discharge between the electrodes to heat the latter to a temperature sufficient to drive off occluded gas and cause the latter to diffuse through the heated quartz envelope, exhausting the outer envelope during the continuance of the discharge for a period of time sufficient to remove the gas therefrom, and sealing off the outer envelope.

2. The method of seasoning high pressure mercury vapor lamps which comprises sealing off the quartz envelope containing the electrodes, mounting the sealed envelope in an outer envelope, energizing the lamp to initiate and sustain an arc discharge between the electrodes to heat the latter to a temperature sufficient to drive off occluded gas and cause the latter to diffuse through the heated quartz envelope, exhausting the outer envelope during the continuance of the discharge for a period of time sufficient to remove the gas therefrom, introducing an inert gas into the outer envelope, and sealing off the outer envelope.

3. The method of seasoning high pressure mercury vapor lamps which comprises applying electrical energy to the electrodes sealed into a quartz envelope to initiate and sustain an arc discharge therebetween for a short period of time to heat the electrodes and drive off occluded gas, exhausting the quartz envelope during continuance of the short period of the discharge, sealing-off 65 the quartz envelope, mounting the lamp in an outer envelope, again applying electrical energy to the electrodes of the lamp to initiate and sustain an arc discharge therebetween for a substantially longer period of time to heat the electrodes to a temperature sufficiently high to drive off sub-

stantially all remaining occluded gas and cause the latter to diffuse through the heated quartz envelope, exhausting the outer envelope during the continuance of the discharge, and sealing-off the outer envelope.

4. The method of seasoning high pressure mercury vapor lamps which comprises sealing-off the quartz envelope containing the electrodes, mounting the sealed envelope in an outer envelope, applying a high voltage current to the electrodes of the lamp to initiate and sustain an arc discharge therebetween to simultaneously heat the electrodes to a temperature sufficient to drive off occluded gas and cause the latter to diffuse through the heated quartz envelope and to bake the outer envelope by the heat from the discharge, exhausting the outer envelope during the continuance of the discharge for a period of time sufficient to remove the gas therefrom, and sealing-off the outer envelope.

5. The method of seasoning high pressure mercury vapor lamps which comprises applying elec-

trical energy to the electrodes sealed into a quartz envelope to initiate and sustain an arc discharge therebetween for a short period of time to heat the electrodes and drive off occluded gas, exhausting the quartz envelope during continuance of the short period of the discharge, sealing-off the quartz envelope, mounting the lamp in an outer envelope, again applying a high voltage current to the electrodes of the lamp to initiate and sustain an arc discharge therebetween for a substantially longer period of time to simultaneously heat the electrodes to a temperature sufficient to drive off substantially all remaining occluded gas and cause the same to diffuse through the heated quartz envelope and to bake the outer envelope by the heat from the discharge, exhausting the outer envelope during the continuance of the discharge for a period of time sufficient to remove the gas therefrom, introducing an inert gas into the outer envelope, and sealing-off the outer envelope.

GEORGE A. FREEMAN.
